UNITED STATES PATENT OFFICE.

HARRY C. BROWN, OF WESTWOOD, NEW JERSEY, ASSIGNOR TO HENRY B. NEWHALL, OF LITTLETON, NEW HAMPSHIRE.

DRILL MECHANISM.

1,217,911.

Specification of Letters Patent.

Patented Mar. 6, 1917.

Original application filed September 20, 1913, Serial No. 790,945. Divided and this application filed July 3, 1914. Serial No. 848,750.

To all whom it may concern:

Be it known that I, HARRY C. BROWN, a citizen of the United States, and a resident of Westwood, in the county of Bergen and State of New Jersey, have invented certain new and useful Improvements in Drill Mechanism, of which the following is a specification, taken in connection with the accompanying drawings, which form a part 10 of the same.

My invention relates to drill mechanism and more particularly to means for feeding the drill point to the work. I have shown my invention in connection with a combination tool illustrated, described and claimed in my co-pending application Serial No. 790,945, filed September 20, 1913, of which this application is a division.

In the accompanying drawings showing 20 illustrative embodiments of my invention and in which the same reference numerals refer to similar parts in the several figures,—

Figure 1 is a longitudinal vertical section through my drill mechanism vise and anvil 25 with which I preferably use it.

Fig. 2 is a transverse vertical section substantially on the line 2—2 of Fig. 1 looking in the direction of the arrows and showing the movable jaw of the vise in side elevation;

Fig. 3 is a transverse vertical section substantially on the line 3—3 of Fig. 1 looking in the direction of the arrows with the hardy omitted;

Fig. 4 is a fragmentary horizontal section substantially on the line 4—4 of Fig. 1;

Fig. 5 is a fragmentary detail side elevation of a portion of the movable jaw showing the pocket for the reception of a portion 40 of the operating screw;

Fig. 6 is a detail vertical section, on an enlarged scale, of the preferred form of telescoping screw threaded member shown in Fig. 1;

Fig. 7 is a fragmentary view of a modification partly in vertical section and partly in side elevation;

Fig. 8 is a perspective view of the operating screw and a fragmentary sectional view 50 of the movable jaw;

Fig. 9 is a plan view of the movable jaw; Fig. 10 is a plan view of the base ring;

Fig. 11 is a detail view of a lathe plate which may be used with my improved drill;

Fig. 12 is a detail showing one of the 55 many tools which may be used with my drill;

Fig. 13 is a detail view showing a different arrangement of mounting one of the many tools which may be used with my device; 60

Fig. 14 is a detail view showing the manner of scoring to form, for example, a key seat.

In the illustrative embodiments of my invention shown in the drawings, 1 is an anvil 65 having a hollow body member 2 and provided with the usual horn 3, and hardy 4, and with a fixed jaw 21. The interior 5 of the hollow body member 2 may be of any suitable configuration to coöperate with the 70 hollow supporting member 6 so that the latter will not rotate within the former. Preferably I provide the opening 5 in the hollow body member of the anvil 1 substantially rectangular in cross section to snugly fit the 75 hollow rectangular supporting member 6. I also provide the hollow body member with additional openings or pockets 7, 7 to co-operate with the locking head 8. This head is so formed as to snugly fit the non-circular 80 opening 5, in one of its positions, so that the locking head 8 can be readily moved in and out to engage with the different pockets or openings 7, 7 upon the operation of a locking bolt 9. 85

This bolt 9 is preferably formed with a square or other non-circular head 10 adapted to be received within the coöperating recess 11 in the locking head 8, its shank passing through the flanged thimbles 12 and 13 90 and coöperating with a nut 14 which serves to prevent the locking bolt 9 from becoming disconnected from the thimbles 12 and 13. The thimble 12 has a flange 15 to engage the end of the rectangular hollow supporting 95 member 6, while the thimble 13 has a flange 16 to coöperate with the inner flange 100 of the standard 17. On the end of the locking bolt 9 I preferably mount an operating handle 18 which I preferably, though not necessarily, provide with a weighted end 19 so that it will normally hang down and hold the locking bolt 9 in the position shown in Fig. 1, which will cause the locking head 8 100

to normally engage some one of the pockets 7, 7. This handle 18 may be secured to the locking bolt in any suitable manner such as by the pin 20.

5 The fixed jaw 21 is preferably provided with an aperture 22, one end of which is provided with a non-circular flaring portion 23 for a purpose to be hereinafter described.

Upon the supporting member 6 I mount 10 the movable jaw 24 of the vise so that it will slide freely providing it with a non-circular opening 25 to snugly receive the supporting member 6. I also provide the movable jaw 24 with an open pocket 26 provided with a 15 U-shaped flange 27, Fig. 5, to coöperate with the groove 28 in the adjusting screw 29. This movable jaw is also provided with an aperture 30 for the reception of the drill press.

20 My drill press which I have shown in connection with my vise, consists, in the preferred form, of a screw-threaded feed member 31 having male screw threads 32 which preferably engage with female screw threads 33 within the screw 29.

25 Within the hollow screw threaded member 31 I mount a drill rod 34 which extends completely through the screw 31, one end 35 of it being preferably formed square to coöperate with the squared opening in the handle 36, a pin 37 being also preferably employed to secure the handle to the drill rod.

The other end of the drill rod is provided 30 with a square or other non-circular head 38 which fits in the non-circular opening 39 in the drill head 40, the arrangement being such that any rotary movement of the handle 36 will cause the drill head 40 to rotate and with it any tool which may be mounted 40 in the drill head socket 41. It is to be distinctly understood that the drill head 40 is rotated independently of the feed screw 31, and yet when desired, the drill head 40 may 45 be held from rotary movement and simply be moved laterally by the screw 31.

50 In practice when rotary movement is imparted to the drill rod 34 to rotate the drill point held in the drill head 40, the friction surface 201 of the drill head 40 will frictionally engage with the surface 200 of the screw threaded feed member 31 and will cause this feed member 31 to rotate at a slower speed and automatically feed the drill head 40 and its drill point to the work.

55 A detachable base ring 42 may be secured upon any work bench or other support 43 by means of screws 44, 44, Fig. 10, this ring being, therefore, for all practical purposes, permanently secured to the work bench. It 60 is preferably provided with a plurality of radiating ribs 45 forming serrations to coöperate with similar serrations 46, on the body member 2. This body member is also provided with a base 47 having a recess 48 65 to receive the head 49 of the pivoting and

locking bolt 50, which extends through the base 47, base ring 42, and through the work bench or other suitable support 43 into engagement with the locking nut 51, operated by any suitable handle 52. The anvil, as 70 well as the entire vise, may be adjusted swivelly upon the base plate 42 into any position which may for the moment be desirable by loosening the locking nut 51 sufficiently to allow the serrations upon the base 75 ring or disk 42 and the hollow body member 2 to pass each other and then tightening the nut 51. This horizontal adjustment may be desirable simply for the anvil portion of the tool, or may be desirable for the vise, or the 80 drill, or all portions of the tool. After being so used the locking nut 51 may be again loosened to permit the entire tool to be swung back to take less room, or when for any reason, it may not be desirable to have it 85 remain in its last adjusted position upon the base ring 42. In case the work bench, or other support 43, is needed for other work, the entire tool, with the exception of the base 90 ring 42, may be instantly removed by unscrewing the locking nut 51 and lifting bodily the entire tool from the work bench, with the exception of the base ring 42, which may be used as an abutment or stop for planing boards or for any other purpose desired. 95 The parts can be immediately repositioned by simply again placing the bolt 50 through the opening in the work bench 43 and bringing the serrations in the base ring 42 in their proper adjusted position.

100 In those cases, where it is desirable to operate the vise so that it will clamp work of different thicknesses, the first rough preliminary adjustment of the movable jaw 24, for work of that particular thickness, is obtained by pulling up upon the weighted arm 19 so as to move the locking head 8 into alignment with the non-circular opening 5 in which position the supporting member 6 may be pushed in or pulled out from the hollow body member 2 to engage any particular pocket 7. The clamping of the particular work 53 is then done by screwing up the screw 29 so that the movable jaw 24 will directly contact with the work 53 or with an 115 intermediate block of wood or other suitable filler 54.

120 Should it then be desired to operate upon the work 53 with the drill, the feed screw 31 is screwed within the screw 29 until the drill point, or other suitable tool, 55 contacts with the work 53 when the drill may be rotated by the handle 36 operating the drill head 40, the drill being seated in the drill pocket 41.

125 The drill is fed forward by suitably operating the feed screw 31. By providing the fixed jaw 21 with the aperture 22, I insure that the point of the drill 55 will not be dulled or broken by contact with the fixed jaw of the vise for when it has passed 130

through the work it will slip harmlessly within the aperture 22.

In those cases where it is desirable to use a very long drill point 55, the screw 31 may be rotated until the drill head 40 becomes adjacent to, or within, some of the female screw threads 33 of the screw 29. Such a long drill point can be inserted through the opening 22 in the fixed jaw 21 and the opening 30 in the movable jaw 24 until it reaches the seat 41 in the drill head 40.

While ordinarily the feed for the drill point is entirely done by the feed screw 31, there are instances in which a preliminary feed may be given by first screwing up the screw 29 and then subsequently screwing the feed screw 31 so that both these screws 29 and 31 may serve as feed screws for the drill point of the drill press as well as one of them, 29, serving to operate the movable jaw 24 of the vice. But in all instances, the work 53 is securely held in the vise without any interference from the operation of the drill.

In case the drill is not often used, it may be temporarily removed by simply unscrewing the feed screw 31 from the screw 29, it being again replaced whenever desired, the combination tool meanwhile occupying less space.

The movable jaw 24 is moved rearwardly upon the rectangular member 6 by the end 56 of the screw 29 fitting within the open pocket 26 of the movable jaw 24 so as to permit the groove 28 to coöperate with the flange 27 on the movable jaw, which will cause the movable jaw to move rearwardly with the screw in an obvious manner. The screws 29 and 31 are operated by their respective handles 57 and 58.

The standard 17 may be formed integral with the supporting member 6 but preferably it is formed separate and snugly fits the supporting member being prevented from becoming disconnected by the flange 16 of the thimble 18 coöperating with the flange 100 of the standard 17. Arranging the parts in this manner permits ready and cheap renewals in case of breakage from any cause.

In some instances I may form the operating screw to operate the movable jaw 59 of the vise with only male screw threads 60, Fig. 7, and provide the feed screw 61 for the drill with male screw threads 62 to engage with female screw threads 63 in the movable jaw 59, though the arrangement previously described is the preferred construction.

My improved tool described is adapted to perform all the functions of an anvil, vise and drill and in addition that of a lathe, thread tap, scoring tool and other numerous uses, these being mentioned simply by way of example.

I have shown in Fig. 11 a lathe plate 64

provided with a square boss 65 to be received in the square drill socket 41 of the drill head 40. When this lathe plate is mounted, for example, on the drill head 40, Fig. 13, and the work 66 is secured to the lathe plate 64 by the clamps 67, the drill point 68 may be placed in the flared non-circular portions 23 of the opening 22, the work then being presented to the stationary drill point 68. The tool then performs the function of a lathe.

I may also tap holes with my improved tool. In Fig. 12 I have shown an intermediate socket 69 to be received within the flaring opening 41 of the drill head 40, the intermediate member being provided with a non-circular opening 70 for the reception of the shank 71 of the tap 72. By the construction shown when the tap 72 begins to cut its screw thread, continued rotation of the drill holder 40 and intermediate socket 69, will cause the tap 72 to rotate and it will cut the threads of the desired pitch regardless of the adjustment of the feed screw 31 for the tap has a free independent axial movement in the socket 70 which permits of its properly cutting its own screw thread by feeding itself regardless of the adjustment of the feed screw 31.

In addition to performing the function of a lathe, my tool also performs the function of scoring or otherwise operating upon wood or metal to form, for example, key seats. I have shown diagrammatically in Fig. 14 a piece of work 84 in which a key seat 85 is being cut by the tool 86 mounted within the drill head 40 by holding the handle 36 of the drill stationary, so that the tool 86 will not rotate, and then operating the feed screw 31 so that it will perform the function of moving the tool 86 longitudinally to score the work 84 to form the key seat 85, or scoring the work 84 for any other desired purpose.

While I have mentioned some of the many advantages of my improved drill and some of the uses to which it may be put, I have not attempted to mention all the uses, but on the contrary it is to be distinctly understood that my invention is not to be confined simply to those uses herein described for it covers any and all uses to which the drill and separate parts may be put and is to be limited only by the terms of my claims.

Having thus described this invention in connection with the illustrative embodiments thereof to the details of which I do not desire to be limited, what is claimed as new and what it is desired to secure by Letters Patent is set forth in the appended claims.

1. In a drill the combination of a plurality of hollow nested screws, a support provided with a screw threaded opening, a drill operating member extending through the screws, a removable drill head detachably

engaged with said member at one end thereof and coöperating with the operating member and of less diameter than the outer screw to permit it to be drawn within the screw, and means to operate the drill operating member.

2. In a drill, the combination of a plurality of hollow nested screws, a support provided with a screw threaded opening, a 10 drill operating member extending through the screw and at one end provided with a drill head, said drill head and one of the feed screws being provided with means adapted to automatically feed the drill head 15 to the work.

3. In a drill the combination of a plurality of hollow nested screws, a support provided with a screw threaded opening co-operating with one of the nested screws, 20 means to quickly adjust the support with its nested screws to and from the work, means to adjust the nested screws with relation to the support to obtain the final adjustment to the work, and a drill operating member extending through the nested screws and 25 adapted to be operated independently of them.

4. In a drill the combination of a plurality of hollow nested screws, a support 30 provided with a screw threaded opening co-operating with one of the nested screws, means to quickly adjust the support with its nested screws to and from the work, means to adjust the nested screws with relation to the support to obtain the final adjustment 35 to the work, and a drill operating member extending through the nested screws provided with means to detachably engage a drill head, a drill head of less diameter than

the outer screw to permit it to be drawn 40 within said screw, and means to operate the drill operating member.

5. In a drill the combination of a plurality of hollow nested screws, a support provided with screw threads to coöperate 45 with one of the nested screws, a drill operating member extending through the nested screws and provided with a drill head, said drill head and one of the nested screws being provided with means adapted to automatically feed the drill head to the work. 50

6. In a drilling tool the combination of a fixed screw threaded support forming an integral portion of the tool, a plurality of hollow nested screw threads mounted within 55 the fixed support of the tool, one of the nested screws provided with screw-threads to coöperate with those of the fixed support, and a drill operating member extending through the nested screws and adapted to be 60 operated independently of either of the screws.

7. In a drilling tool the combination of means to hold the work to be drilled said means being operated by a nested screw, a 65 fixed screw threaded support forming an integral portion of the tool, a plurality of hollow nested screws mounted within the fixed support of the tool, one of the nested screws provided with screwthreads to co-operate with those of the fixed support, and a drill operating member extending through the nested screws and adapted to be operated 70 independently of either of the screws.
